[57] ABSTRACT

An improved water motor for automatic sprinkling systems provides a selected sprinkling pattern which is reversed 180° upon reversal of the direction of water motor rotation. Thus a section of ground immediately in front of each driving motor of the sprinkling system is left dry until the drive means passes. To this end, a rotatable sleeve valve disposed within the water motor defines manifold means which allows water to pass from the water motor nozzles only during selected arcuate portions of rotation thereof. The reversal of the direction of water rotation automatically rotates the sleeve valve 180° to reverse the direction of the sprinkling pattern. Further, the improved water motor may be readily disposed with the output shaft from the motor extending through the pipeline in selected configuration, to allow preferred location of the water motor at a selected height above the pipeline and thus at an optimum height above the ground level.

FIG. 1

WATER MOTOR WITH PARTIAL CIRCLE PATTERN

BACKGROUND OF THE INVENTION

1. Field

The invention relates to automatic sprinkler systems and particularly to an improved water motor for generating a selected partial-circle water pattern which is automatically reversible in response to the water motor direction of rotation.

2. Prior Art

In the operation of an automatic, self-propelled sprinkling apparatus having towers for driving the system it is preferable to irrigate in a half (or greater) circle pattern to keep the ground dry immediately in front of each water tower as it proceeds across the field carrying the sprinkler system. Partial circle sprinklers are available which are coupled to the pipeline itself and which are adapted to direct the sprinkler water to the rear of the line of pipe; i.e., which generate a sprinkling pattern only to the rear of the sprinkler system pipeline. However, when employing the water motors of previous mention to propel the pipeline, the motor will throw water to the front of the tower even if the sprinklers do not. In addition, upon reversal of the water motor as, for example, in reversing the direction of travel of the pipeline across the field, there is no provision on the prior art water motors for reversing the direction of the sprinkling pattern; i.e., no apparatus which reverses the direction in which the water is sprinkled such that it is always directed to the rear of the pipeline regardless of the pipeline direction of movement. Thus in prior art sprinkling systems, reversing the direction of the pipeline travel causes water to be sprinkled ahead of the associated water towers from the water motors and the motors must be all manually adjusted to correct the sprinkling pattern.

Additionally, when water powered sprinkling systems are used in fields of tall growing plants, such as corn, it is desirable to position the pattern generating water motors at as high a level as possible in order to prevent the motor arms from tangling in the plants. Accordingly, the motor is adaptable for location above the irrigation pipeline, within the frame of the water tower. The height to which the motor can be raised is thus limited only by the A-frame structure of the tower, not the height of the pipeline. Locating the water motor directly over the pipe, with the drive shaft extending through the pipeline in accordance with the invention, allows the motor to be raised to its maximum height within the A-frame structure.

SUMMARY OF THE INVENTION

The invention provides an improved water motor configuration which contemplates a partial-circle, water pattern generating means integral therewith, which is responsive to the direction of rotation of the water motor. The water pattern generating means includes a rotatable sleeve valve disposed within the water motor spinner. The sleeve valve includes passageways which define manifold means for blocking the passage of pressurized water through the water arms/nozzles as they rotate through a selected angle extending forwardly of the respective water towers. When the direction of the water motor rotation is reversed (generally by swivelling the arms/nozzles through 180°)

the friction between the sleeve valve and the water motor spinner automatically reverses the water pattern direction 180°.

Further the invention combination contemplates a sealed sleeve means disposed through the pipeline to define a shaft supporting means, whereby the water motor may be located at a maximum height within the water tower structure. The drive shaft from the improved water motor extends accordingly through the pipeline to the gear drive mechanism of the water tower.

BRIEF DESCRIPTION OF THE DRAWINGS

FIG. 1 is a perspective of one support tower of the usual plurality of water towers in an automatic sprinkling system showing a section of the sprinkler pipeline and a respective water motor of the invention.

FIG. 2 is a cross section of the apparatus for generating a partial-circle sprinkling pattern in accordance with the invention combination.

FIG. 3 is a cross section taken along section line 3—3 of FIG. 2.

FIG. 4 is a cross section of the means for elevating the water motor to its maximum height above the pipeline.

DESCRIPTION OF THE PREFERRED EMBODIMENTS

Referring to FIG. 1, there is shown by way of example, a support tower 12 and a corresponding section of a pipeline 14 of an automatic sprinkling apparatus 10, such as described for example in the copending U.S. applications Ser. No. 805,664 filed Mar. 10, 1969 and Ser. No. 27,226 filed Apr. 10, 1970, said applications being assigned to the same assignee as this application.

The support tower 12 includes an A-frame 16, supported upon a pair of wheels 18 each having its own pivotable, wheel-supporting, fork 20. As depicted, each support tower 12 is propelled by a respective water motor 22, the output of which is coupled to the wheels 18 via an output drive shaft 24 and gear train means 26, such as those described in the above mentioned copending U.S. applications, but adapted as in accordance with the invention. The A-frame 16 includes a horizontal, pipe supporting, cross member 28 and a horizontal, water motor supporting, cross member 30, for supporting the pipeline 14 and the water motor 22, respectively.

The water motor 22 includes a water spinner 32 and a water motor direction reversing means 34 integrally disposed therewith, of the type described for example in copending U.S. application Ser. No. 96,008 filed Dec. 8, 1970, now U.S. Pat. No. 3,687,373 said application also being assigned to the same assignee as this application. The spinner 32 is rotatably supported by the water motor supporting cross member 30, and is rotatably coupled at the upper end thereof to a source of pressurized water introduced to the motor 22 via a conduit 36 which extends from the pipeline 14 along portions of the A-frame 16, to the pipeline 14.

The water motor 22 is coupled at the lower end of the spinner 32 to the output shaft 24, which extends downwardly through the pipeline 14 via a shaft supporting means 38 in accordance with the invention. By way of example only, the sprinkling pattern generated

by the partial-circle, pattern generating means of the water motor 22, is depicted by shading in FIG. 1 and by the numeral 40, illustrating the manner in which the improved water motor 22 of the invention provides a dry section immediately before the support tower 12. The spinner 32 is thus adapted to include the partial circle, pattern generating means (FIGS. 2 and 3) which is automatically reversed to reverse the direction of the sprinkling pattern relative to the direction in which the sprinkling system moves, upon reversal of the direction of rotation of the water motor 22.

Referring to FIGS. 2 and 3, there is shown the means for generating the partial circle sprinkling pattern; i.e., for providing a selected water motor sprinkling pattern to define a dry section immediately in front of the respective tower, in accordance with the invention. The direction of the sprinkling pattern is automatically reversed when the water motor direction of rotation is reversed, whereby the dry section is again disposed in front of the support tower when it proceeds in the opposite direction.

To this end, the water spinner 32 includes a water spinner housing 42 with bores 44, 46 and 48, 50 (FIG. 3) formed in opposite walls thereof, wherein opposing pairs of water arms 52, 54 and 56, 58 are affixed to the spinner in register with respective bores. Note although four water arms (and integral nozzles, not shown) are illustrated here, any other number of arms may be used with the pattern generating mechanism of the invention.

The drive shaft 24 is demountably coupled, in this example, to the spinner housing 42 via a flared bell portion 60, which is tightly fitted within the housing and pinned with a pin 62, or may be threadably connected and pinned, welded, etc. A cylindrical, water directing, sleeve valve 64 is rotatably disposed within the spinner housing 42 and extends coaxially through a central opening 66 in the flanged top end of the housing 42. A bore 68 is coaxially formed along most of the length of the sleeve valve 64, and a 180° radially extending arcuate slot 72 is formed through the side wall of the valve in communication with the bore 68, to provide manifold means for selectively directing water to a maximum of three of the four water arms 52-58 at any one time. Thus as the housing 42 and associated water arms 52-58 rotate relative to the sleeve valve 64, the water arm (or arms) which is temporarily not in communication with the arcuate slot 72 has water blocked therefrom and therefore does not eject any water.

The sleeve valve 64 is provided with circumferentially extending seal means 74, 76 disposed in associated grooves axially spaced at either side of the bores 44-50. The upper end of the sleeve valve 64 is provided with a rotatable arcuate stop 78. The arcuate stop 78 extends through one quadrant of the sleeve valve rotation, and abuts an arcuate fixed stop 80, which also extends through one quadrant. The stop 80 is formed on the end of a cylindrical support member 82 which is rigidly secured as by welding to the water motor supporting cross member 30 (FIG. 1) in register with a hole therethrough. A flanged cylinder 84 is rigidly secured to the cylindrical support member 82, with the flanged end confronting a support ring 86 welded concentrically about the upper end of the sleeve valve 64.

The arcuate stop 78 is coextensively secured to, or formed of, the support ring 86. A valve seal 88 is confined between the confronting surfaces of the flanged cylinder 84 and the support ring 86. Pressurized water is supplied to the water spinner 32 via the conduit 36 which may be welded to the cross member 30 in register with the cylindrical support member 82, or which may be demountably coupled thereto via suitable connector means (not shown).

In operation, when the water motor direction is reversed, the friction force exerted on the sleeve valve 64 is sufficient to cause it to rotate for at least a part of a circle with the water spinner 32, relative to the flanged cylinder 84 and the cylindrical support member 82. Thus the sleeve valve 64 rotates until the (rotatable) arcuate stop 78 meets the (fixed) arcuate stop 80. The stop 80 is oriented relative to the support tower to provide the dry section of the sprinkling pattern along a selected direction of tower travel, viz., to the front of the tower. When the motor is reversed, the sleeve valve 64 is rotated through 180° via friction with the housing 42, until the opposite ends of the stops 78, 80 meet, thus rotating the arcuate slot 72 through 180° to automatically reverse the sprinkling pattern direction.

Note that the length of the arcuate slot 72 may be increased or decreased from the 180° cross section shown in FIG. 3, to provide a correspondingly narrower or wider dry section within the sprinkling pattern, to adapt the sleeve valve 64 to a water motor configuration having for example only one, two, etc. arms, or to provide any desired partial-circle pattern.

In prior art self-propelled irrigation systems, the water motors are placed below the pipe means 14. However it is most usually desirable to place the water motor as high as possible so that the motor arms will not become entangled with the growing crop.

If the water motor 22 is raised by offsetting to the side to allow the drive shaft 24 thereof to extend downwardly alongside (rather than through) the pipeline 14, the rotatable arms thereof would contact one side of the A-frame 16 at a relatively low height above the pipeline. To allow the disposition of the water motor at the maximum level immediately above the pipeline, the invention includes a shaft supporting means 38 disposed in sealed relation through the pipeline 14 at each water motor position, whereby the drive shaft 24 may extend downwardly through, rather than alongside or below, the pipeline, whereby the motor may be raised to a maximum height.

To this end, referring to FIG. 4, the shaft supporting means 38 for rotatably supporting the water motor above the pipeline 14, is shown in cross section. A sleeve 90 having an internal diameter substantially larger than the diameter of the drive shaft 24, is welded at either end thereof to diametrically opposed holes 92, 94 in the pipeline 14. The water motor 22 is disposed above the pipeline (FIG. 1) and the drive shaft 24 therefrom extends downwardly through the sleeve 90, and through a hole in the pipe supporting cross member 28. A bushing 96 is secured within the sleeve 90 to reduce "chattering" etc., of the shaft 24 as it rotates within the sleeve 90. The central disposition of the water motor 22, shaft 24, etc., allows the motor to be raised to its maximum height within the given height of the A-frame 16 in accordance with the invention combination.

What is claimed is:

1. An improved water motor for propelling the water towers of sprinkling apparatuses, wherein a source of pressurized water is connected to said water motor, the improvement comprising: a motor body including a rotatable spinner, at least one water arm and associated nozzle extending radially from the rotatable spinner and affixed thereto, valve means integral within the rotatable spinner and automatically responsive to the direction of rotation thereof, said valve means including manifold means for delivering water to but a portion of the circumference of said spinner at any one instance for generating a selected water pattern defining a dry section immediately in front of the respective water tower.

2. The improved water motor of claim 1 wherein said valve means comprises a cylindrical sleeve valve including therein said manifold means, for impeding the flow of water to the associated water arms and integral nozzles during a selected angular portion of the water motor rotation.

3. The improved water motor of claim 2 wherein the cylindrical sleeve valve is rotatably disposed concentrically within the water motor spinner in sealed relation, and the manifold means includes a coaxially extending bore in communication with the pressurized water, a radial slot formed therethrough in communication with the coaxial bore at its inlet and in register with selected successive water arms at its outlet, support means for rotatably supporting the cylindrical sleeve valve within the spinner, and stop means integral with the support means and the sleeve valve to limit the angular rotation of the sleeve valve with respect to the support means,

said sleeve valve being rotatable through a limited arc in response to friction between it and the water motor spinner.

4. The improved water motor of claim 3 wherein said radial slot has an arcuate length disposed in register with at least one water arm and integral nozzle to define the selected sprinkling pattern.

5. The improved water motor of claim 4 wherein said radial slot has an arcuate length disposed in register with a plurality of said water arms and integral nozzles to define the selected sprinkling pattern.

6. The improved water motor of claim 1 further including, means associated with said improved water motor for selectively positioning the water motor in rotatable relation above the pipeline at each tower location.

7. An improved water motor for propelling the water towers of moving-while-sprinkling apparatuses wherein a source of pressurized water is connected to said water motor, the improvement comprising: a motor body including a rotatable spinner with at least one water arm and nozzle extending radially from the spinner, valve means within the rotatable spinner including manifold means for delivering water to but a portion of the circumference of said spinner at any one instance for generating a selected water pattern defining a dry section immediately in front of the respective water tower, and means for selectively positioning said water motor including sleeve means disposed in sealed relation through the pipeline for rotatably positioning the water motor a selected height above and in line with the pipeline.
